UNITED STATES PATENT OFFICE.

CHESTER E. KINARD, OF COOPER, TEXAS, ASSIGNOR TO THE COOPER AUTOMATIC CAR DOOR CO., OF COOPER, TEXAS.

DOOR-HANGER.

1,110,944.

Specification of Letters Patent. Patented Sept. 15, 1914.

Application filed May 7, 1914. Serial No. 836,987.

To all whom it may concern:

Be it known that I, CHESTER E. KINARD, a citizen of the United States, residing at Cooper, in the county of Delta and State of Texas, have invented certain new and useful Improvements in Door-Hangers; and I do declare the following to be a full, clear, and exact description of the invention, such as will enable others skilled in the art to 10 which it appertains to make and use the same.

This invention relates to improvements in car doors and more particularly to hangers therefor.

15 The primary object of the same is to provide a hanger of the character described which is constructed in such a manner as to normally take the weight of the door off the supporting rollers and the track.

20 A secondary object is to construct the hanger in such a manner as to apply a braking action to the track simultaneously with throwing the supporting rollers out of play, thus preventing the door from unnecessarily 25 shifting.

With the above objects in view, the invention resides in certain novel features of construction and combination herein described and claimed and shown in the drawings 30 wherein:

Figure 1 is a side view of a portion of a car showing the door closed and the supporting rollers thrown out of action; Fig. 2 is a similar view with the door raised and 35 the rollers in position to travel on the track; Fig. 3 is a detail transverse section on the line 3—3 of Fig. 1; and Fig. 4 is a detail perspective view of one of the levers on which the supporting rollers are journaled.

40 In the embodiment illustrated, I have shown a portion of a freight car 1 having the usual door opening 2, sliding door 3, track 4, guides 5 for the lower end of said door, and stops 6 for preventing excessive 45 movement of the latter in either direction.

The door 1 may be of any suitable construction and is of slightly less height than the distance between the upper face of the guides 5 and the lower face of the track 4, 50 this provision being made for a purpose to appear. Rigidly secured to the upper corners of the door 1 are upwardly extending arms 7 which extend a suitable distance above the track 4, and have their free ends

offset in such a manner as to bring them directly above the active face of said track as 55 at 8.

Pivottally mounted upon the upper ends of the arms 7 are inwardly extending levers 9 which are here shown as being formed of single strips of strap metal bent substantially upon themselves and having their central portions turned outwardly as at 10 for the reception of supporting rollers 11 which are journaled therein and are adapted to 60 travel on the track 4. Depending from the outer side of each lever 9 is an arm 12 which has its lower end turned inwardly beneath the track 4 to provide friction shoes 13 which are adapted to contact with the lower 65 face of said track in a manner to be described. The inner ends of the levers 9 are pivoted to offset terminals 14 or links 15, which are pivoted at 16 to the upper end of a connecting rod 17. The connecting rod 70 75 17 is slidably mounted through a guide 18 on the door 3 and is provided, on its lower end, with a ring 19 in which an eccentric 20 operates for raising or lowering the inner 80 ends of the levers 9. The eccentric 20 may be provided with any suitable operating handle 21 for obvious reasons.

The operation of the device is as follows: Assuming that the door is open and supported upon the rollers 11, and it is desired 85 to retain the same in this open position, the handle 21 of the eccentric 20 may be turned to such a position as to move the inner ends of the levers 9 upwardly. This action will allow the door 3 to lower and rest upon the 90 guides 5 and will also cause the rollers 11 to rise out of contact with the track 4 and will bring the friction shoes 13 into binding contact with the underside of said track. It will be evident that the above operations 95 will clamp the door 3 securely between the guide 5 on which it rests and the underside of the track 4 and will prevent any shifting thereof.

When it is desired to again close the door, 100 the eccentric may be turned in the proper direction for bringing the rollers 11 into contact with the track and for rocking the levers 9 around the roller journals, and thus raising said door out of contact with the 105 guide 5. The door may then be closed and locked in closed position by means of any suitable locking mechanism L. The door

may be left in this position, but is preferably again lowered until it rests upon the guides 5, thereby relieving the track 4 of the weight of said door.

- 5 Should the door be left partially open and supported upon the track 4 and rollers 11, it would remain in this position as long as no sudden jar were imparted to the car. If, however, the car should be violently shaken by the process of coupling another car thereto, the jar of said operation will cause the eccentric 20 to turn around its pivot 22 and will thus allow the door to drop into contact with certain of the guides 5.
- 10 15 I consider the provision of the friction shoes 13 an extremely important feature of my invention, since by their action, the door may be locked in any desired position. The specific structure of said shoes also prevents the rollers 11 from jumping the track 4 when said rollers are raised or lowered, as the case may be.
- 20 25 I have described my invention with considerable minuteness, but I do not wish to

be limited to details of construction, other 25 than those amplified in the appended claim.

Having thus described my invention, what I claim as new and desire to secure by Letters Patent is:

The combination with a sliding door, 30 guides for the lower end thereof, a track, and supporting rollers adapted to travel thereon, of levers pivotally connected at one end to said door and carrying the journals for said rollers intermediate their ends, links 35 pivoted to the free ends of said levers, a connecting rod pivoted to said links, a ring on said connecting rod and an eccentric journaled on said door and operating within said ring for raising or lowering said lever 40 for the purpose set forth.

In testimony whereof I have hereunto set my hand in presence of two subscribing witnesses.

CHESTER E. KINARD.
